Primary Examiner — Calvin E Vansant*Assistant Examiner* — Cheng Chen(74) *Attorney, Agent, or Firm* — Andrus Intellectual Property Law, LLP(57) **CLAIM**

The ornamental design for an outboard motor as shown and described.

DESCRIPTION

FIG. 1 is a front perspective view of an outboard motor according to our new and ornamental design;

FIG. 2 is rear perspective view thereof;

FIG. 3 is a right-side elevation view thereof;

FIG. 4 is a left-side elevation view thereof;

FIG. 5 is a front elevation view thereof;

FIG. 6 is a rear elevation view thereof;

FIG. 7 is a top view thereof; and,

FIG. 8 is a bottom view thereof.

The broken lines illustrate portions of the outboard motor that form no part of the claimed design.
